US00D531117S

(12) **United States Design Patent** (10) **Patent No.:** **US D531,117 S**
(45) **Date of Patent:** **** Oct. 31, 2006**

(54) **BATTERY MODULE**

(75) Inventors: **Steven M. Schrick**, Knoxville, TN (US); **Albert L. Lee, IV**, Seymour, TN (US); **William S. Groh**, Knoxville, TN (US)

(73) Assignee: **Radio Systems Corporation**, Knoxville, TN (US)

(**) Term: **14 Years**

(21) Appl. No.: **29/243,180**

(22) Filed: **Nov. 21, 2005**

(51) **LOC (8) Cl.** **13-02**

(52) **U.S. Cl.** **D13/103**

(58) **Field of Classification Search** D13/102-106, D13/110, 118-119, 184; 429/96-100, 163, 429/176

See application file for complete search history.

(57) **CLAIM**

The ornamental design for a battery module, as shown and described.

DESCRIPTION

FIG. 1 is a perspective view of a battery module of the present invention;

FIG. 2 is a front elevation view of the battery module shown in FIG. 1, the rear view being identical thereto;

FIG. 3 is a left side elevation view of the battery module shown in FIG. 1, the right side elevation view being identical thereto;

FIG. 4 is a top plan view thereof; and,

FIG. 5 is a bottom plan view thereof.
